DRILL SHARPENER

Wilbert Orville Benning, Los Angeles, Calif.

Application June 8, 1942, Serial No. 446,173

3 Claims. (Cl. 51—219)

My invention relates to a drill sharpener, the primary object being to provide effective means for quickly and accurately sharpening twist drills. A further object is to provide a device of its kind which will aid the machinist in grinding the points of drills accurately and with predetermined clearance, whereby the drill will perform its function by a clean cut and without dragging or over-heating. A still further object is to provide a device which can be easily adjusted to determine the angle of the point of the drill and the amount of clearance at which the drill is sharpened. A still further object is to provide a drill sharpener which is simple and inexpensive in construction and which is readily adapted for use in grinding twist drills of various lengths and diameters, which is readily adjustable to regulate the angle and clearance at which the drill is sharpened, and the application of the drill to the abrasive element longitudinally, which will not easily get out of order, and which is not subject to wear after long continuous use.

To these ends, my invention comprises the features of construction and combination of parts hereinafter described and claimed.

In the accompanying drawings forming part of this specification, Fig. 1 is a side elevation of my improved drill sharpener, portions thereof being broken away; Fig. 2 is a plan of the structure shown in Fig. 1; Fig. 3 is a side elevation of the drill holder separate from the device; Fig. 4 is a plan of the drill holder; Fig. 5 is a front end elevation of the drill sharpener when the drill holder is in horizontal position; Fig. 6 is an end elevation of the slide of the drill holder; Fig. 7 is a side elevation of a portion of the slide and the abutment shown in Fig. 6; Fig. 8 is a plan of the corresponding parts shown in Fig. 7; Fig. 9 is an end view of the cutting end of a twist drill such as is adapted to be sharpened by my improved drill grinder, and Fig. 10 is a diagrammatic plan illustrating the manner in which a twist drill is adapted to be sharpened by my improved drill sharpener.

In the drawings, A is a flat base which may be of any suitable shape upon which, as shown is an abrasive wheel B of usual type, revolved by the prime mover such as the electric motor indicated by C, the latter being mounted in stationary position on the base and revolvably supporting the abrasive wheel. D is a turn-table revolvably mounted so as to revolve in a horizontal plane on the base about an axis formed by the pivot 18. The turn table functions as a

main supporting base and is swung upon its pivot by hand, a suitable handle 11 radiating from its periphery being provided. E is a supplemental support consisting of a table or plate 5 resembling a segment superimposed above the turn table. This segment is pivoted about an axis formed by the pin 12, eccentric to the axis of the turn table so as to swing independently in the plane of and upon or about said table. An arcuate slot 13 near the periphery of and through the segment and a binding screw 14 having its shank passing downwardly through said slot and threaded into the turn table serves to releasably fasten the segment in adjusted position circumferentially about its axis upon the surface of the turn table. A scale 15 inscribed in the surface of the turn table and a cooperating pointer 16 on the periphery of the segment serve to aid the operator in regulating the degree 10 at which the segment is adjusted in a horizontal plane about its axis for the purpose to be hereinafter described.

F is a pedestal mounted rigidly upon the supplemental supporting segment upon the upper 25 end of which is tiltingly mounted to swing in a vertical plane a twist drill holder G. This holder has a body formed by a pair of parallel horizontally spaced flanges 17 connected transversely at their upper extremities by a longitudinal cradle 30 18, in which the twist drill such as H is adapted to be held with its cutting edge juxtaposed for sharpening against the work side surface of the rotatable abrasive wheel B. Extending rearwardly from said body is an integral longitudinal slide 19 above which the rearward body end 35 of the shank of the drill extends freely from the supporting cradle. The flanges 17 straddle the upper end of the pedestal F and the drill holder tilts in a vertical plane on a horizontal shaft 20. An arcuate slot 21 through one of the flanges 17 and a binding screw 22 having its shank passing through said slot and threaded into the body of the pedestal serve to fasten the drill holder in vertically and forwardly inclined position to 40 present the cutting edge of the drill to the work surface of the abrasive wheel so as to sharpen the drill with the desired taper. A scale 23 inscribed on the surface of one of the flanges adjoining the fastener 22 and a cooperating stationary pointer 24 on the pedestal, serve to aid the operator in regulating the degree of taper at 45 which the drill holder is adjusted at inclined position.

The slide 19 in cross section resembles a channel opening horizontally and having a longitudi-

nal toothed rack 25 in its inner portion. Arranged to travel longitudinally on the slide is an abutment I which functions as a back stop for resting the drill bit with its cutting end juxtaposed to the abrasive work surface of the rotating abrasive wheel. This abutment resembles a carriage or collar closely conforming so as to slide freely longitudinally on the slide. The carriage holds a ratchet 26 which is pivoted at 27 between a pair of bosses 28 therein and has an inwardly extending toothed rack engaging end 29 and a hand depressing arm 30 projecting outwardly through an opening 31 in the carriage. The rack engaging end 29 is pressed into engagement with the rack teeth by the expansion spring 32. Normally the ratchet engages the rack to prevent rearward movement of the abutment but when the operating arm is depressed the ratchet is disengaged and the abutment can be regulated as described in approximate adjustment along the slide. The upper side of the abutment above the slide has a pair of bosses 33 and 34 cooperating with the body of the abutment to form a longitudinal bearing through which is threaded a longitudinal stop shaft 35. The inner end of this shaft has a swiveled bearing head 36 which presses against the end of the shank of the drill to form a back stop and adjustably sustain the drill with its cutting end coincident with the work surface of the abrasive element. A knurled barrel 37 in the abutment I and threaded on the back stop shaft provides a hand operable adjustment by the rotation of which said shaft can be regulated to rest the drill longitudinally. The forward portion 38 of the back stop shaft is polygonal in cross section and slides in a corresponding passage in the forward boss 34 to hold the shaft from turning when the adjusting barrel 37 is revolved.

In use the drill to be sharpened is laid longitudinally in the cradle where it is held by hand with its work end to be sharpened adjusted to the work surface of the abrasive wheel and its shank sustained by the abutment as shown in Figs. 1 and 2. Two primary adjustments are provided by the structure which are apparent from the diagrammatic views shown in Figs. 9 and 10: first, for sharpening the opposite cutting edges 40 at the desired forward taper and, second, for cutting the surfaces 41 back of the cutting edges at the desired angle of clearance so as to enable the cutting edges to perform their function of cutting effectively when the drill is used. The drill holder is inclined downwardly to sharpen the drill by the abrasive element at the desired angle of taper forwardly in the drill holder. The angle of inclination for producing the taper of the cutting edges 40 is regulated by tilting and setting the holder on its horizontal axis according to the concentric scale 23 and tightening the binding screw 22. First one cutting edge is sharpened and then the other by turning the drill over. While the drill is held in the cradle of the holder the abutment is adjusted with the head of the back stop shaft planted back of and against the rearward end of the shank of the drill so as to rest the drill longitudinally during the entire grinding operation.

Following the grinding and sharpening of each cutting edge of the drill at the desired taper the turn table D is swung slowly in its horizontal plane forwardly to the left about the pivot 18, causing the holder with the drill therein to swing through an arc 44 (see Fig. 10), horizontally and cut the end surface back of each cut-

ting edge to produce the desired clearance. By adjusting the segment E about its eccentrically disposed axis 12, according to the scale 15, the angle and amount of clearance at which each surface 41 is ground is regulated. The adjustment of the parts of the device both in a vertical and horizontal plane can be easily and quickly made to accommodate drills of a wide range of sizes both in diameter and length.

10 The drill sharpener can be provided with any suitable abrasive wheel trimmer, such as J for trueing the work surface of the abrasive wheel from time to time when it becomes worn or uneven, said trimmer being allowed to remain inactive when not in use by swinging down upon its journal support 50.

Operation

When operating my improved drill sharpener, 20 the drill holder G is first set at the desired angle in a vertical plane according to scale 23 to apply the cutting end of the drill in the holder to the side of the abrasive wheel B so as to sharpen the cutting edge 40 with the desired taper by the subsequent grinding operation. In this position the holder is secured by the binding screw 22. The pedestal F is next set according to a scale 15, to the desired clearance angle in which 25 position it is secured by the binding screw 14. The twist drill such as H to be sharpened is placed with its work end in the cradle 18 and with its shank extending rearwardly above the slide 19. The abutment I is next adjusted along the slide to an approximate position juxtaposed to the rearward end of the drill and with the feed stop 36 abutting the drill shank. The twist drill is then fed forwardly toward the side of the abrasive wheel by turning the adjusting barrel 37 until the drill contacts the abrasive wheel. 30 Both sides of the drill should be cut with each advance of the twist drill towards the abrasive wheel to secure even results. Very light cuts are desirable in order to secure the best results. Each forward step of the feed and forward cut should 35 be followed with a clearance cut by rotating the turn table to the left.

The two cutting edges of the drill should incline at the proper angle and at the same corresponding inclination to the longitudinal axis 50 of the drill and should be of corresponding length. The clearance angle is important as insufficient clearance causes splitting of drills through the web and excessive clearance weakens the cutting edge. The clearance of the surfaces following the cutting edges required also varies according to the character of material which is drilled. The adjustment of the clearance provided by the horizontal adjustment of the drill holder G on the rotatable table D enables the operator to provide the proper clearance by my improvement at which the drill is sharpened.

In accordance with the patent statutes, I have described the principles of operation of my invention, together with the apparatus which I now consider to represent the best embodiment thereof, but I desire to have it understood that the structure shown is only illustrative and that the invention can be carried out by other means and applied to uses other than those above set forth within the spirit of the invention and within the scope of the following claims.

I claim:

1. A twist drill sharpener, comprising, a base, a turn table journaled to revolve in a horizontal plane upon said base, an abrasive element hav-

ing a work surface in a plane normal to the turn table, a support journaled to revolve in a horizontal plane on the turn table about an axis eccentric to the axis of the turn table and coincident with the work surface of the abrasive element, a drill holder freely tiltable to swing in a vertical plane upon said support and normally inclined downwardly to present the work end of a drill to the work surface of the abrasive element with its cutting surface within full view of the operator and cause the sharpening of the cutting edge of the drill at a forwardly tapering angle, means for holding the drill holder adjusted in tilted position so as to maintain a fixed angle at which the drill is cut, said turn table when rotated about its axis causing the abrasive surface of the abrasive element to cut the drill with a clearance surface back of the cutting edge thereof defined by the eccentric position of the drill holding means on the turn table, and means for fastening said support adjusted in an arc about its axis to establish the angle of clearance cut by the abrasive surface back of said cutting edge.

2. In a structure as defined in claim 1, the work holder having a cradle disposed longitudinally for holding a drill with its cutting end

juxtaposed to the work surface of the abrasive element, a rack extending longitudinally on the cradle, a carriage slideable longitudinally upon the cradle, releasable engaging means on the carriage for engagement with the teeth of said rack for holding the carriage in selected longitudinal position on the cradle, and a micrometer adjustment on the carriage for engaging and advancing a drill when held in the carriage toward the work surface of the abrasive element.

5 3. In a structure as defined in claim 1, the drill holder being disposed longitudinally in the direction of the abrasive surface of the abrasive element for holding a drill with its cutting end 15 juxtaposed to said abrasive surface and having a longitudinal rack, a carriage slideable longitudinally on the work holder in the vicinity of said rack, ratchet means on the carriage for releasably engaging the teeth of the rack and holding the carriage in selected longitudinal position on the work holder, and an adjustor on said carriage having micrometer precision for engaging the rearward end of a drill and advancing the latter with its cutting end directed against 20 25 the abrasive surface of the abrasive element.
